UNITED STATES PATENT OFFICE.

WILLIAM K. JONES, OF WICHITA, KANSAS.

UNION-SUIT.

1,206,543.

Specification of Letters Patent. Patented Nov. 28, 1916.

Application filed June 8, 1915. Serial No. 31,936.

To all whom it may concern:

Be it known that I, WILLIAM K. JONES, a citizen of the United States, and a resident of Wichita, in the county of Sedgwick 5 and State of Kansas, have made an Improvement in Union-Suits, of which the following is a specification.

My invention relates to an improved construction and arrangement of the rear portion 10 of a union or combination suit, whereby certain advantages are obtained in respect to attachment, adjustment, and manipulation of the jacket flap or skirt and the drop flap.

15 The details of the invention will be understood from the following description, taken in connection with the accompanying drawing, in which,

Figure 1 is a perspective view of the garment applied to a person. Fig. 2 is a rear view showing the drop flap in the lowered position. Fig. 3 is a longitudinal section on the line 3—3 of Fig. 1. Fig. 4 is a rear view showing the skirt of the body or jacket 25 unbuttoned and turned up.

The jacket 1 and legs 2 are constructed and connected to form one garment. The skirt or rear flap 3 of the jacket 1 is provided at its lower corners with button holes 30 4—see Fig. 2—which adapts the same to be secured detachably to the buttons 5, which are fastened to the side edges of the pants 2 at points below the waist-line of the jacket. The drop flap 6 is also provided at 35 its upper corners with button holes 7, which adapt it for detachable connection with buttons 8 secured to the jacket above the waist line.

An elastic suspender attachment 9 is secured to the back of the jacket 1 at a point about midway between the arms, and the drop flap 6, is detachably secured to buttons 10. The latter is constructed with a hook as used in this class of devices to permit 45 ready engagement and disengagement, as conditions require.

It will be seen that the skirt portion 3 of the jacket extends downward from the waist line and lies beneath the drop flap 6

and is secured to the buttons 5, so that it is held normally in that position. It is further apparent that this engagement or fastening of the drop flap to the sides of the legs must be made before the drop flap is pulled up and attached to the suspender. Consequently, when the wearer of the garment bends over forward, the skirt 3 is not pulled out of the drop flap at the waistband, and, when the wearer resumes erect position, the skirt is pulled down smoothly by the movement of his body, by reason of the attachment of the same to the buttons 5, as before stated.

The arrangement is one adapted to well protect the wearer from dirt and permits the free use of the two hip pockets 11 attached to the outer side of the seat portion of the trousers, since they are not covered at any time.

I claim:—

1. The improved union garment comprising a jacket or body portion having buttons 5 and 8 secured, respectively, below and above the waist-line, a jacket flap extending down below the waist line and having button holes adapted for engagement with the lower set of buttons attached to the jacket, and a drop flap having button holes at its corners for engagement with the buttons 8 located on the jacket above the waist line, 80 the drop flap when closed thus covering the lower portion of the jacket flap as described.

2. The improved union garment comprising a jacket or body portion having fastening devices 5 and 8 secured respectively below and at the waist line, a jacket flap extending down and below the waist line and adapted for engagement with the lower portion of the jacket, and a drop flap having its corners constructed for engagement with the fastening device located at 8 on the jacket, the drop flap when closed thus covering the lower portion of the jacket flap, as described.

WILLIAM K. JONES.
